UNITED STATES PATENT OFFICE.

HENRY C. OSBORN, OF CLEVELAND, OHIO, ASSIGNOR TO THE AMERICAN MULTIGRAF COMPANY, OF CLEVELAND, OHIO, A CORPORATION OF OHIO.

PRINTING MACHINE.

Application filed May 16, 1925. Serial No. 30,658.

This invention relates to office printing machines primarily adapted for printing on envelopes, cards, tags and the like. One of the objects of the invention is to provide for the effective printing on objects of various thicknesses without adjustment. Another object is to enable the presence of the article to be printed to cause the printing movement of a normally idle printing device, thus insuring each article being printed, while preventing the smudging of the platen by the transfer of ink thereto when the article is absent.

Other objects of the invention are to provide for the ready change of the printing characters or a portion thereof as desired, and generally to render the construction cheap, efficient and durable.

My printing machine is well adapted for cancelling stamps, as it is adapted to operate equally well on articles of various thicknesses arranged indiscriminately. The machine however may with advantage be put to other uses. The machine is preferably arranged so that the same installation may be driven either by power or by hand as desirable at the time.

A convenient embodiment of my invention is illustrated in the drawings hereof, and is hereinafter more fully described and the essential characteristics are summarized in the claims.

In the drawings Fig. 1 is a front elevation of my printing machine, the paper table being removed and the hand crank being broken away; Fig. 2 is a sectional side elevation of such machine showing the paper table in place, the plane of the section being indicated by the line 2—2 on Fig. 1, looking toward the left; Fig. 3 is a detail of gearing which may be employed, being a section on the line 3—3 of Fig. 1 looking toward the right; Fig. 4 is a vertical central transverse section of the machine as indicated by the line 4—4 on Fig. 2; Fig. 5 is a transverse section on an off-set plane indicated by the line 5—5 on Fig. 2; Fig. 6 is an elevation of the controlling linkage system shown in Fig. 2, the controlling disks and platen being indicated by broken lines; Fig. 7 is an edge view of such linkage system; Fig. 8 is a cross-section through the segment of the printing drum as indicated by the line 8—8 in Fig. 1; Fig. 9 is a detail, illustrating means for holding the type form

on the segment, this view being a cross-section indicated by the line 9—9 on Fig. 8; Fig. 10 is a perspective of one of the type holding rails, a type and the lock therefor.

The frame of my machine is shown as consisting of a pair of upright end plates 10 and 11, a connecting front cross plate 12 and certain cross rods. Journaled in the end plates is the main shaft 20 on which is mounted the printing segment 30, adapted when released to be revolved thereby, and carrying the printing form, and below this main shaft is a shaft 50 on which is mounted the roller platen 52 adapted to coact with the printing segment. A suitable inking roller 130 coacts with the segment when rotated. Accordingly as the shafts 20 and 50 are revolved, paper fed between the segment and platen may be suitably impressed by a type form on the segment.

The type segment is yieldingly carried so that it may give back from the platen according to the different thicknesses of material fed between them. To effect this, I mount on the shaft 20 a sleeve 22, carrying a disk 23 at one end of the sleeve, and a double arm 24 and 25 at the other end. The hub portion 26 of this double arm is shown as secured to the end of the sleeve by screws. The segment 30 near one end has an inward ear 31 which lies between the disk 23 and the arm 25, and a pin 32 occupying these parts pivots the segment to the rotatable member.

To a block 33 rigid on the inner face of the segment near its other end is pivoted a rod 34 which extends loosely through a pin 35 carried by the rigid arm 24. Nuts 36 on this rod limit the outward movement of the segment while a compression spring 37 surrounding the rod between a head 38 thereon and a washer 39 loose on the rod and bearing against the pin 35 yieldingly holds the segment in printing position but allows it to give back according to the thickness of the material fed between the segment and platen.

The type form is carried on the convex face of the segment 30 at some distance from its pivoted end. I have shown this portion of the segment as provided with rails 40 which are grooved on their sides as shown at 41, Figs. 9 and 10, to receive type 42 grooved on its sides so that the head of the type rests on top of the rails 40, while the

feet project into the grooves 41. The type may be readily slid into place endwise of the segment and locked therein by suitable blocks 43 (Figs. 8 and 10) which may be held by screws passing into the segment.

The segment coacts with a suitable platen which is shown as a long roller 52 mounted on a shaft 50 which is geared with the shaft 20 by a pinion 55 on the platen shaft, meshing with a gear 56 on the segment shaft. Either of these shafts may constitute the driver. I have shown a crank 60 mounted on the shaft 20, and I have shown the pinion 55 as connected by an idler 57 with a pinion 58 on a shaft 59 which carries at its other end a driving pulley 62. Accordingly, the machine may be operated either by hand power applied to the crank 60 or mechanical power applied to the pulley 62, as desired.

As heretofore stated, one of the objects of this invention is to provide effective means insuring the operation of the printing device when the paper is fed, while preventing it when the paper is not fed. I accomplish this by making the printing device loose on the shaft 20 and normally locked against rotation but adapted to be frictionally driven by that shaft when the paper frees the lock. The mechanism for accomplishing this will now be described.

As shown in Fig. 4, the disk 23 bears against a fiber washer 70 which bears against a disk 71 secured to the shaft 20 by a pin 72 occupying a groove in the disk. On the opposite side of the portion 26 of the segment carrier is a fiber washer 74. Beyond this is a loose collar 75 which is pressed toward the washer by a compression spring 76. The spring surrounds the shaft and bears at its far end against a collar 77 clamped in adjusted position on the shaft. By this means suitable frictional pressure is caused to exist on opposite ends of the segment carrier, so that it will be readily rotated to effect printing whenever it is free to rotate, but when locked will allow the shaft 20 to rotate independently of the carrier.

The lock for the segment carrier is best shown in Figs. 2 and 6, and comprises a dog 80 on a lever 81 journaled on a sleeve 83 loose on a cross rod 82 mounted in the end plates. A spring 84 between the lower end of this lever and the end plate 10 tends to swing the upper end of the lever toward the segment carrier and bring the dog into position to engage a shoulder 85 provided by a notch in the edge of the disk 23 as shown in Fig. 2. The dog 80 is preferably pivoted to the lever 81 but is normally retained against a pin 87 on the lever by a tension spring 88. This spring allows the dog to yield and thus act as a shock absorber in stopping the rotation of the segment carrier.

The mechanism described normally maintains the segment locked in stationary posi-

tion though the shaft 20 is normally rotating. A lever 90 pivoted at 91 to the end plate 10 is connected by a link 93 to the lower portion of the lever 81. The upper end of the lever 90 carries a roller 95 which bears against the edge of the rotating disk 71, being constrained in that direction by a spring 96 connected to the lower end of the lever and to the end plate. At one region in the periphery of the disk 71 is formed a notch 97 and when this notch comes opposite the roller, the spring 96 may swing the lever 90, moving the roller into the notch and pulling forwardly on the link 93, to pull the dog 80 rearwardly to free the segment carrier, whereupon the latter will be drawn through the frictional connection with the rotating shaft 20.

The unlocking movement of the linkage system just described is normally blocked by the rock arm 100 on the sleeve 83, which arm stands with its end in front of a block 99 on the lever 90 as shown in Fig. 2. The arm 100 is connected with a feeler finger 101 which is pinned to the end of the sleeve 83 and extends forwardly above the platen, normally lying in a groove 102 therein, and curved upwardly in front of the line of impression and above the plane of the paper table.

If material to be printed is shoved rearwardly into position between the segment carrier and the platen, it will come beneath the turned up end of the finger 101 and raise it, thereby rocking upwardly the arm 100 out of the path of the block 99, and then when the notch 97 comes opposite the roller 95, the spring 96 will swing this roller into the notch and pull on the link 93 to swing the lever 81 to withdraw the dog 80 from the shoulder 85, the parts thus coming into the position shown in Fig. 6. This unlocks the platen carrier so that it may be rotated by friction by the rotating shaft 20 and thus cause printing on the material, as well as the rearward feed and discharge thereof.

It should be noted that the notch 85 is so positioned with reference to the printing segment 30 that the segment carrier stands, normally with the printing face just in front of the printing position. Accordingly almost immediately after the release of the segment, by means of the paper raising the finger 101, the segment comes into coaction with the paper to print upon it and continue its feed.

The paper may be manually advanced to gripping position at any period of the cycle and will ordinarily lift the finger 101 to remove the arm 100 from the stop 99, so that whenever the notch 97 comes opposite the roller 95, the release of the segment carrier is effected. It will be seen from Fig. 2 that when the roller 95 is bearing on the circular position of the periphery of the

disk 71, there is a slight clearance between the block 99 and the end of the arm 100, which allows the latter to be easily raised by the insertion of the paper beneath the 5 arm 101.

Since the paper may be inserted while the notch 97 is opposite the roller 95, when the block 99 is bearing against the arm 100, I provide a yielding connection between the 10 finger and the arm 100. As shown, the finger 101 is rigid on one end of the sleeve 83 which carries at its other end an arm 104 which is connected by a spring 105 with the arm 100. Accordingly, if the paper is 15 inserted beneath the finger 101 at a time when the pressure of the block 99 against the end of the arm 100 prevents its movement, the spring 105 will simply be stretched, and then as soon as the notch 97 passes the 20 roller 95 so that the pressure is relieved on the arm 100, the spring will lift the same free from the block 99 and the carrier will be released when the notch 97 again comes opposite the roller 95. When so released 25 the block 99 lies below the end of the arm 100 as shown in Fig. 6 so that the latter may not drop until the notch has passed beyond the roller.

As soon as the notch 97 has moved past 30 the roller 95, the lever 90 will be swung, its lower end moving rearwardly, and as the dog 80 is then opposite the circular periphery of the disk 23, the lower end of the lever 81 cannot move rearwardly at that time. 35 Accordingly, I provide some loose play in the connection between the levers, preferably by means of a slot 119 in the link 93.

The paper or other articles to be printed are fed to the printed couple automatically 40 or manually as desired. The drawing illustrates at 110 a paper table along which the articles may be shoved by hand. A stop finger 112 having an upturned end is provided which occupies an annular groove 113 in the platen and normally stands with the upturned end projecting through a shield strip 114 secured at a forward end above the paper table and at the rear end to the rod 82, or in some other similar manner. 45 The upturned end of the stop finger is located adjacent to the line of coaction of the printing member and platen. This stop finger is carried by the lever 90 and is rocked down to idle position whenever the lever 50 is rocked to effect the release of the segment carrier.

As this lever 90 is ordinarily returned to active position, before the paper has passed beyond the stop finger, I provide a yielding connection between the latter and the lever 90. As shown, the stop finger has a vertical ear 115 by which it is loosely pivoted to the lever 90. Rigid on this lever is a short arm 116 lying against the ear. The ear carries 55 a pin 117 beneath the arm, while a spring

118 seated in a socket in the arm bears against the under-side of the finger. Accordingly, the finger and its yielding anchorage is rocked down as a unit when the notch 97 comes opposite the roller 95, but 70 on the return stroke the finger may press against the under-side of the paper without damage thereto, the spring 118 being quite light so as to avoid any injury by the upturned end of the finger. 75

As soon as the paper, fed rearwardly beneath the shield strip 114 and against the end of the stop finger 112, has been released by the swinging down of the stop finger and has been gripped by the type segment and platen it is drawn rearwardly and printed thereby. In such rearward travel, its forward edge comes over the ejection roller 120 which is tightly mounted on the shaft 59 and thus rotated with its top surface traveling toward the rear. Resting on this roller is a roll 121 mounted in a trough shape arm 122 pivoted on the rod 82 and pressed downwardly by a coil spring 124. This roll 121 lies lightly upon the paper and thus causes 80 its effective ejection. The discharged printed article drops at the rear of the machine, being guided downwardly by the inclined shield 126 which is shown as mounted on a frame rod 127 and as secured at 128 to the 85 end plates.

As heretofore stated, the printed segment may be readily inked on each rotation by engagement with the inking roller 130. This roller may be of the form shown in Fig. 5 100 and comprises a felt sleeve, or felt disks mounted side-by-side, on a bushing 131, locked thereon by a nut 132.

To adjust the pressure of the inking roller against the segment to vary the amount of 105 ink to be transferred, I prefer to mount the spool described on a sleeve 135 which is mounted on an eccentric portion 136 of a shaft 137. One end of this shaft is journaled in a frame plate 10 and carries beyond that member an arm 138 by which it may be rocked, while a screw 139 passing through a slot in the arm serves to lock it in the desired position. The other end of the shaft 137 is preferably journaled within a 110 socket in the end of a stud 140 which is carried by a frame member 11. This stud carries a pinion 142 which meshes with the gear 56 on the shaft 20. Projecting from the pinion are a pair of pins 143 which occupy 115 radial slots 144 in a collar 145 rigid on the shaft 135. This coupling enables the gear to rotate the roller continuously irrespective of the adjustment of the roller by the eccentric mounting toward or from the segment 120 path.

It will be seen from the drawings and description that my machine is simple in construction and that it may receive articles of varying width and thickness, as for instance, 125

from a thin sheet to a catalogue of a number of pages or a letter with several enclosures. The feeding of the article may be performed at any stage of the cycle, and it is simply necessary for the operator to give the article a slight rearward shove, after which the machine will automatically grip such article and effect the printing and the discharge. This feed may be done manually while the machine is being driven by power or being rotated by the other hand of the operator. My machine may be used for many purposes, and is particularly well adapted, for instance, for use as a stamp canceller in offices which do not require elaborate automatically fed stamp-cancelling machines.

Having thus described my invention, I claim:

1. In a printing machine, the combination of a rotary carrier, a printing segment pivoted at one end to the carrier, a rod pivoted to the segment adjacent the other end, and slidable through a guide on the carrier, and an adjustable nut on the rod retarding the outward movement of the segment.

2. In a printing machine, the combination of a rotary carrier, a printing segment pivoted at one end to the carrier, a rod connected to the segment adjacent the other end, and a compression spring surrounding the rod retarding the inward movement of the segment.

3. In a printing machine, the combination of a rotary carrier, a segment pivotally mounted at one end on the carrier, and spring pressed outwardly adjacent its other end, arcuate rails on the segment, and grooved type mounted between said rails.

4. In a printing machine, the combination of a rotary carrier comprising a disk at one end of a hub and a pair of arms at the other end, a segment pivoted between one of the arms and the disk, and a spring acting on the segment and bearing against a pin between the other arm and the disk.

5. In a printing machine, the combination of a rotary platen, a rotary carrier mounted on a parallel axis, a printing segment pivoted to the carrier, and spring-pressed outwardly, a friction drive for the carrier, a latch adapted to prevent rotation of the carrier, and a paper actuated member for releasing the latch.

6. In a printing machine, the combination with a printing member and platen, of a finger adapted to be raised by paper moved beneath it, an abutment removed by said finger from the path of mechanism which by other power removes a stop normally preventing the activity of the couple, whereby the movement of said finger may control the coaction between the printing member and platen without overloading the finger.

7. In a printing machine, the combination of a rotatable printing member, means for

rotating the member, a latch adapted to restrain its movement, means controlled by the rotating means to release the latch, an abutment normally in the path of movement of the releasing means, a finger adapted to be raised by the insertion of paper to be printed, and mechanism associated with the finger whereby the raising of the finger causes the removal of the abutment.

8. In a printing machine, the combination of a normally inactive rotary printing couple, means for rotating the same to print, a latching mechanism normally restraining the printing coaction, a member controlled by the rotating means for temporarily preventing the feeding of material to be printed, an operating connection between said member and the latch, and means movable by the material in position to be printed for simultaneously rendering such connection effective to release the latch and to allow the feeding of the material.

9. In a printing machine, the combination of a normally stationary printing member, means for moving said member, a rotary platen coacting therewith, a raisable finger extending transversely of the line of coaction of the printing member and platen and occupying an annular groove in the platen, said finger being adapted to be raised by paper passed beneath it, a latch mechanism for preventing movement of the printing member, operable by said moving means and during a certain portion of the cycle of its movement to release said printing member, and means whereby the raising of the finger places said mechanism into condition to be operated.

10. In a printing machine, the combination of a pair of printing members one of which is normally inactive, a driving means to render the latter active, means for maintaining such inactive relation, and a movable member normally interposed in the path of paper to be printed, said member having a connection with the maintaining means whereby when such material is presented to the printing members said movable member acts to cause the driving means to release the maintaining means.

11. In a printing machine, the combination of a normally stationary rotary carrier, a printing segment mounted on the carrier, a platen with which the printing segment coacts, a finger extending transversely of the line of coaction of the printing member and platen adjacent the path of travel of the segment, and adapted to be raised by the insertion of paper, a latch for preventing movement of the carrier, a normally moving driving mechanism for the carrier, a cam operated thereby for controlling the movement of the latch to release the carrier, and an abutment for preventing such releasing movement, said abutment being con-

1. nected with said finger for operation thereby.
2. In a printing machine, the combination of a normally stationary rotary carrier, a segment pivoted to the carrier and spring pressed outwardly, type removably mounted on the convex face of the segment, a rotary platen with which such type is adapted to coact, the platen and type serving to feed the paper rearwardly, a finger adapted to be moved by the paper, a latch for preventing movement of the carrier, and mechanism whereby the movement of the finger may result in the release of the latch.
3. In a printing machine, the combination of a normally stationary printing member, a normally moving cam, means whereby the cam is adapted to periodically initiate the movement of the printing member, a paper actuated finger, and mechanism controlled thereby adapted to prevent such operation by the cam.
4. In a printing machine, the combination of a rotary printing member, a latch adapted to hold it stationary, a rotary cam, mechanism periodically actuated thereby and adapted when unobstructed to release the latch, mechanism normally obstructing such operation, and a paper actuated finger for releasing the last mentioned mechanism.
5. In a printing machine, the combination of a rotary printing member, a latch for holding it stationary, a friction drive tending to rotate the printing member, a normally moving cam, mechanism periodically actuated thereby for releasing the latch, and a device controlled by the presence or absence of the article to be printed for determining the effectiveness of the last mentioned mechanism.
6. In a printing machine, the combination of a rotary printing member, a friction drive therefor, a platen coacting with the printing member, a latch for preventing movement of the printing member, a cam adapted to periodically release the latch, a finger extending transversely of the line of coaction of the printing member and platen, and adapted to be raised by the material to be printed upon, and means blocking the effectiveness of the cam-operating mechanism, said means being adapted to be moved to idle position by the raising of such finger.
7. In a printing machine, the combination of a rotary carrier, a segment pivotally mounted thereby, and spring-pressed outwardly, printing characters mounted on the convex face of the segment, a platen with which said characters may coact, a friction drive for the carrier, a latch adapted to hold the carrier stationary, a rotary cam, mechanism between the same and the latch, whereby by the cam may release the latch, a raisable finger extending transversely between the printing member and platen and adapted to be raised by the insertion of material to be printed, and a normal obstruction to the release of the latch removed by the raising of said finger.
8. In a printing machine, the combination with a platen, of a rotary printing member, a latch adapted to hold the printing member stationary, a rotary cam, a lever having a roller coacting with the cam, means connecting said lever with the latch, whereby when the roller responds to the cam the latch may be released, and a paper controlled device for blocking such movement.
9. In a printing machine, the combination of a rotary printing member, a lever carrying a dog adapted to prevent movement of the printing member, a friction drive tending to move the printing member, a rotary cam operated in unison with the friction drive, a lever adapted to be moved by a cam, and a connection between said lever and the lever first mentioned.
10. In a printing machine, the combination with a rotary platen, of a rotatable shaft parallel therewith, a pair of disks one tight on the shaft and the other loose thereon, a cam on the tight disk, a printing member carried by the loose disk, a latch for the printing member, and mechanism operated by the cam for releasing the latch.
11. In a printing machine, the combination with a rotary platen, of a rotatable shaft parallel therewith, a cam tight on the shaft, a printing member loose on the shaft, a latch for the printing member, mechanism operated by the cam for releasing the latch, a raisable finger extending between the printing member and platen, means normally preventing the cam releasing the latch, and means whereby said finger when raised by the paper withdraws said preventing means.
12. In a printing machine, the combination of a rotary printing member normally stationary, a latch for the printing member, a stop finger adapted to retard the insertion of the paper, a cam, and means whereby the cam may cause the release of the latch and withdrawal of the stop finger.
13. In a printing machine, the combination of a rotary printing member normally stationary, a rotary cam normally moving a latch for the printing member, a roller actuated by the cam, a linkage system between the roller and latch, a stop finger adapted to retard the insertion of the paper, and means whereby the actuation of the linkage system by the cam withdraws the stop finger.
14. In a printing machine, the combination of a rotary printing member normally stationary, a rotary cam normally moving, a latch for the printing member, actuating mechanism for the latch adapted to be operated by the cam, a stop finger adapted to

retard the insertion of the paper, and means whereby the operation of said actuating mechanism by the cam withdraws the stop finger, a finger adapted to be engaged by the 5 paper, means normally blocking the operation of said actuating mechanism, and means whereby the movement of said finger withdraws said blocking means.

25. In a printing machine, the combination 10 of a rotary platen, a rotary printing member normally stationary, but adapted to coact therewith, a rotary friction drive therefor normally moving, a rotary cam normally moving, a latch for the printing member, a

roller actuated by the cam, a linkage system 15 between the roller and latch, a stop finger adapted to retard the insertion of the paper, means whereby the actuation of the linkage system by the cam releases the latch and withdraws the stop finger, a raisable finger 20 extending between the printing member and platen, and means for normally blocking the operation of the linkage system, and means whereby the raising of said finger withdraws said blocking means. 25

In testimony whereof, I hereto affix my signature.

HENRY C. OSBORN.
